Primary Examiner — T. Chase Nelson*Assistant Examiner* — Mark Cavanna(74) *Attorney, Agent, or Firm* — Kilpatrick Townsend & Stockton, LLP(57) **CLAIM**

The ornamental design for a wearable monitoring device, as shown and described.

DESCRIPTION

FIG. 1 is a front perspective view of a wearable monitoring device, showing a first embodiment of our new design;

FIG. 2 is a front view thereof;

FIG. 3 is a back view thereof;

FIG. 4 is a left side view thereof;

FIG. 5 is a right side view thereof;

FIG. 6 is a top elevation view thereof;

FIG. 7 is a bottom elevation view thereof;

FIG. 8 is a front perspective view of a wearable monitoring device, showing a second embodiment of our new design;

FIG. 9 is a front view thereof;

FIG. 10 is a back view thereof;

FIG. 11 is a left side view thereof;

FIG. 12 is a right side view thereof;

FIG. 13 is a top elevation view thereof; and,

FIG. 14 is a bottom elevation view thereof.

The broken lines in FIGS. 6-9 and 11-14 are for environmental purposes only and form no part of the claimed design.
